UNITED STATES PATENT OFFICE

ADELE W. KEHLER, OF SAN FRANCISCO, CALIFORNIA

DESIGN FOR A COMBINED CIGARETTE AND MATCH CONTAINER

Application filed March 27, 1931. Serial No. 39,261. Term of patent 7 years.

To all whom it may concern:

Be it known that I, ADELE W. KEHLER, a citizen of the United States of America, residing at San Francisco, in the county of San Francisco and State of California, have invented a new, original, and ornamental Design for Combined Cigarette and Match Containers of which the following is a specification, reference being had to the accompanying drawings, forming a part thereof.

I claim:—

The ornamental design for a combined cigarette and match container substantially as shown and described.

ADELE W. KEHLER.
